CLAIM

The ornamental design for an electric tree limb trimmer, as shown and described.

DESCRIPTION

FIG. 1 is a side elevation view of an electric tree limb trimmer showing our new design with the opposite side being a mirror image thereof;

FIG. 2 is an enlarged, fragmentary top plan view of the cutting end of the electric tree limb trimmer;

FIG. 3 is an enlarged, fragmentary bottom plan view of the cutting end;

FIG. 4 is a fragmentary cross-sectional view taken along line IV—IV of FIG. 1;

FIG. 5 is an enlarged, fragmentary front elevation view of the cutting end;

FIG. 6 is a reduced scale top plan view of the electric tree limb trimmer shown in its entirety;

FIG. 7 is a bottom plan view thereof;

FIG. 8 is a front elevation view; and,

FIG. 9 is a rear elevation view.

The views of FIGS. 2-5 have been shown in a fragmented manner for clarity of illustration.

FIG. 6

FIG. 8

FIG. 9

FIG. 7
